UNITED STATES PATENT OFFICE.

LUCIUS W. POND, OF WORCESTER, MASSACHUSETTS.

STEAM-GENERATOR.

SPECIFICATION forming part of Letters Patent No. 340,060, dated April 13, 1886.

Application filed November 23, 1885. Serial No. 183,748. (No model.)

To all whom it may concern:

Be it known that I, LUCIUS W. POND, a citizen of the United States, residing at Worcester, in the county of Worcester and State of Massachusetts, have invented a new and useful Improvement in Steam-Generators, of which the following is a specification, accompanied by drawings, in which—

Figure 1 shows a vertical sectional view of a steam-generator embodying my invention, and Fig. 2 is a transverse sectional view of the same with the boiler removed.

Similar letters refer to similar parts in the several views.

15 My invention relates to that class of steam-generators which embody a boiler having a flat side or crown-sheet, on which the water rests, and which forms the heating-surface; and my invention consists in the construction 20 of the boiler and fire-pot, as hereinafter described, and in the combination of a guard-plate with the fire-pot.

A is the fire-pot, of cast-iron, having a grate, B, and made with its upper part flaring at C, 25 forming a rim, a, whose diameter is considerably larger than the diameter of the fire-pot itself. Within the rim a, I place a series of spurs, b, upon which the boiler rests; or, instead of the spurs b, another and interior annular rim may be formed having openings corresponding to the spaces c between the spurs b, as shown. A series of openings, d, 30 through the fire-pot form flues, through which the products of combustion pass to the outside 35 of the fire-pot. Within the fire-pot is a shell or lining, D, inclosing an air-space between it and the wall of the fire-pot, through which air is admitted, by means of small openings e at the bottom and e' at the top, to the interior 40 of the fire-pot, thereby aiding in the more perfect combustion by the admission of fresh air to the section of the fire-pot occupied by the gases liberated from the coal, and also protecting the outer wall of the fire-pot from the action 45 of the fire.

The boiler consists of the shell E and a plate, F, forming the crown-sheet, joined at its edge to the flanged rim f of the shell E, preferably by bolts f', passing through an annular ring, f'', by which the edge of the crown-sheet is 50 securely clamped between the ring f'' and the flange f; or the annular ring f'' may be omitted

and the heads of the bolts may be "squared" and brought directly against the under side of the crown-sheet. A ring, g, is attached concentrically to the interior surface of the crown-sheet F, the surface in contact with the crown-sheet being limited to that immediately surrounding the attaching-bolts, so as to secure a water-tight joint. A tripod, h, is attached to 55 the ring g, and a screw-threaded bolt, i, whose head rests against the outer surface of the shell E, is screwed into the tripod to resist the strain resulting from the steam-pressure. The diameter of the crown-sheet is slightly smaller 60 than that of the rim a, which is higher than the tops of the spurs b, so the boiler will be retained in position with the annular ring f'' resting on the spurs b.

The base-plate G, forming the top of the 70 ash-box H, supports a sheet-metal case, I, surrounding the fire-pot and boiler, and having a smoke-pipe, J.

A cast-metal guard-plate, K, is placed around the fire-pot opposite the flue-openings 75 d, having an air-space between it and the case I, to prevent the current of heated air from impinging against the sheet-metal case. Equidistant prongs or spurs L extend outwardly from the rim of the fire-pot to sustain the 80 guard-plate, and are bent downward to carry the lower edge of the guard-plate below the flue-openings d, the ribs j serving to brace the prongs L, and also stiffen the flaring shell of the fire-pot.

Upon the guard-plate I usually place a sheet-metal conical shell, M, forming a lining to the outer case, I.

Pipes m m' allow steam to be taken from and the water of condensation to be returned 90 to the boiler in the ordinary manner.

It has been customary in steam-generators of this class to fasten both the crown-sheet and shell to the fire-pot, requiring a water-tight joint to be made and maintained between those 95 portions forming the boiler proper and the fire-pot, which has been difficult, owing to the unequal expansion of the walls of the fire-pot, which are subjected directly to the intense action of the fire and the shell of the boiler, 100 which is brought in contact with the water and its temperature restricted within 212° Fahrenheit.

In the construction herein shown the only

water-tight joint required to be maintained is between the shell E and crown-sheet F, both of which are in contact with the inclosed body of water N. The stay-rod *i* may be applied 5 and the amount of tension regulated after the boiler has been constructed, the dome E itself acting as a brace.

I do not confine myself to the special form 10 of dome shown; neither do I claim, broadly, the fire-pot having spurs upon which the boiler rests; but

What I do claim as my invention, and desire to secure by Letters Patent, is—

1. A steam-generator consisting of a fire-pot and a shell or dome having a flange around its lower edge, and a plate or crown-sheet attached at its edges to said flanged edge of the shell or dome, forming a water-tight boiler, said boiler resting upon said fire-pot, but disconnected therefrom, as described, and for the purpose set forth.

2. The steam-generator consisting of a fire-pot and a water-tight boiler resting on but disconnected from said fire-pot, said boiler 25 consisting of a shell or dome, its lower edge forming a flange, an annular ring corresponding with said flange, and a plate or crown-sheet having its edge clamped between said flange and annular ring, which are firmly

drawn together, as described, and for the purpose set forth.

3. In a steam-generator, the combination, with a fire-pot having its top flaring and having a series of spurs supporting the boiler, and a rim inclosing the edge of the boiler, said rim having a series of flue-openings, of a boiler 35 consisting of a shell and crown-sheet, as described, and for the purpose set forth.

4. The combination, with a steam-generator consisting of a flaring fire-pot and a boiler 40 resting thereon, as described, said fire-pot having a flue-opening and an inclosing-case, of a series of prongs projecting outwardly from said fire-pot, and a guard-plate held by said prongs opposite the flue-openings of the fire-pot, as described, and for the purpose set forth.

5. The combination, with the boiler of a steam-generator, consisting of a shell or dome and a plate or crown-sheet, of a stay-rod whose head rests upon the outer surface of the shell 50 or dome, and whose inner end is attached to said crown-sheet, substantially as described, and for the purpose set forth.

LUCIUS W. POND.
